UNITED STATES PATENT OFFICE.

FRANCIS W. COOPER AND HENRY STEADWORTHY, OF MONTREAL, QUEBEC, CANADA.

RAIL-ANCHOR.

1,366,558.

Specification of Letters Patent. Patented Jan. 25, 1921.

Application filed December 19, 1919. Serial No. 346,101.

To all whom it may concern:

Be it known that we, FRANCIS W. COOPER and HENRY STEADWORTHY, both subjects of the King of Great Britain, and residents of the city of Montreal, in the Province of Quebec and Dominion of Canada, have invented certain new and useful Improvements in Rail-Anchors, of which the following is a full, clear, and exact description.

This invention relates to improvements in rail anchors, and the object of the invention is to provide an inexpensive, durable and efficient anchor having resilient means for securing it to a rail, whereby the anchor will not become loosened by vibration.

A further object is to provide an anchor which is neither right-handed nor left-handed, but may be applied against either of two adjacent ties and either inside or outside a rail.

The device consists briefly of a body member of substantially U-shape notched toward the extremities of its arms for the reception of the edge of a rail base and adapted to receive between its arms below the rail base a spring hook engaging the opposite edge of the rail base, and a wedge holding the hook and body in rail engaging position.

In the drawings which illustrate the invention:—

Figure 1 is a side elevation of the device in position on a rail.

Fig. 2 is an end elevation of the device.

Figs. 3 and 4 are views similar to Fig. 1 illustrating slight modifications.

Fig. 5 is an end elevation of the device shown in Fig. 4.

Referring more particularly to the drawings, 11 designates a rail base having a substantially horizontal or plain lower surface 12 and an upper surface 13 sloping upwardly from the edges toward the centrally disposed web 14.

The anchor comprises a body 15, and a retaining hook 16, and if desired a wedge 17. The body is preferably formed of a flat strip of metal bent into U-form and having a pair of similar parallel arms 18 connected by a web 19. Each arm is provided with a notch 20 located in an edge thereof and toward the free end of the arm and designed for the reception of the edge of the rail base. These notches are so disposed that the web 19 lies at a greater inclination than

the upper surface of the rail base above it, the inclination of the web 19 being preferably about double the inclination of the upper surface 13. The notches 20 are preferably of such dimension that the body 15 makes a tight driving fit on the rail base before the edge of the base quite reaches the bottoms of the notches, so that the anchor will accommodate itself to slight variations of rail base thickness.

The hook 16 comprises a flat strip of resilient material turned up at one end 21 to engage the opposite edge of a rail base from the body and having a flat central portion 22 underlying the rail base and extending between the arms of the body. Beyond the flat portion, the strip is bent back under itself, as at 23, and terminates in a flat portion 24 lying on the web 19 of the body and having its extremity abutting against the flat central portion 22. The portion 23 constitutes a very stiff C spring.

The wedge 17 is tapered to fit snugly between the rail base and the hook and to have full surface engagement with both when the hook is bearing against the web of the body 15. This wedge is of such length that its head 25 will project slightly beyond the body when it is fully driven home. As clearly seen in Fig. 2, the width of the wedge is substantially equal to the width of the hook and both substantially fill the space between the body arms so that no unnecessary play is allowed.

In the form shown in Fig. 3, the curved or spring portion 23 of the hook is slightly larger in diameter and the hook bears directly against the rail base, the wedge 17 being omitted.

In Figs. 4 and 5, the hook 116 comprises a flat central portion 122 having an upturned end 121 and at the sides a pair of downturned triangular flanges 126 adapted to bear at their lower edges on the web of the body. The body and wedge are exactly identical with these parts as described in connection with Figs. 1 and 2.

The operation of the device is extremely simple. In the forms shown in Figs. 1, 2, 4 and 5, the body is driven onto one edge of a rail base, the hook inserted through the body and its tip engaged with the opposite edge of the rail base. The wedge is now inserted between the hook and rail base and driven as tightly as desired. In this driving, the wedge presses downwardly upon

the hook to such an extent that the hook slips downwardly on the inclined web of the body and draws its tip very tightly against the edge of the rail base. This 5 downward slip of the hook is obviously accompanied by a drawing of the body toward the center of the rail and, at the same time, the body is drawn downwardly by reason of the action of the wedge. The wedge 10 being held by the resilient hook cannot be worked loose by vibration. The form of device shown in Fig. 3 is applied in a slightly different manner. The body is driven onto the edge of the rail base, as 15 with the other forms, and the hook inserted as before. Pressure is then applied to the hook, preferably at about the point and in about the direction indicated by the arrow to compress the spring portion 23 and 20 move the hook through the body until its tip 21 slips up over the edge of the rail base. The expansion of the hook between the divergent surfaces of the rail base and body web urges the hook to movement in 25 a retreating direction, so that its tip is drawn tightly against one edge of the rail base and it operates to draw the body against the other edge of the rail base.

The advantages of this device are chiefly 30 the resilient holding means which make it proof against loosening by vibration, combined with its simplicity, inexpensiveness and efficiency. The bite on the rail obtained by making the body a driving fit is 35 very great from the outset and when pressed against a tie by rail movement, any oscillating tendency or cant serves only to increase the grip. The body projects cornerwise into the ballast, so that pounding in frozen ballast 40 will have no loosening effect. The disposition of the surfaces is such that they drain readily and do not interfere with drainage of the road bed. The two members of the anchor being relatively slidable, 45 the anchor will automatically adjust itself to different widths of rail base within a predetermined range. While the wedge has been shown as driven between the hook member and the rail, it will be understood 50 that the same results exactly will be obtained by driving the wedge between the hook member and the body web, but such an arrangement of the parts would render assembly extremely awkward, if not im- 55 possible. While the form of hook shown in Fig. 4 has been illustrated only in conjunction with a key, it will be obvious that the body and hook may be assembled on a rail without the key, as indicated in Fig. 3; 60 the body being flexed during driving and its resiliency serving to hold the turned-up tip against the rail edge.

Having thus described our invention, what we claim is:

65 1. In a rail anchor, a body adapted to

engage one edge of a rail, a hook adapted to engage the other edge of the rail and extend transversely of the rail through the body, and a key arranged to hold the body and hook in engagement with one another 70 and with a rail.

2. A device according to claim 1, in which the key is inserted between the hook and the base of the rail.

3. A device according to claim 1, in which 75 the key is a wedge driven through the body transversely of and beneath the rail and in contact with the lower face of the rail base.

4. A device according to claim 1, in which the hook is wedge-shaped in the portion en- 80 gaging the body.

5. In a rail anchor, a U-shaped body notched toward the extremities of its arms to embrace one edge of a rail base, said notches being arranged to dispose the central portion of the body at a greater inclina- 85 tion than the upper surface of a rail base, and a hook member engaging the opposite edge of the rail base and arranged in compression between the lower surface 90 of a rail base and the sloping central portion of the body.

6. A device according to claim 5 in which the body engaging portion of the hook is wedge-shaped.

7. A device according to claim 5 in which 95 the hook member is resilient and holds the body to the rail by its expansive force.

8. In combination with a device accord- 100 ing to claim 5, a key holding the hook in compression.

9. In combination with a device accord- 105 ing to claim 5, a wedge-shaped key driven between the hook and lower surface of the rail base transversely of the rail.

10. A device according to claim 5, in which the hook is a strip of resilient metal bent upon itself within the body.

11. In a rail anchor, a body comprising 110 a strip of metal bent transversely to form a pair of parallel arms connected by a central web, said arms being notched to embrace the edge of a rail base and the notches being arranged to dispose the central web in a plane having greater inclination than the plane of the upper surface of the rail base and in the same direction, and means adapted to hold said body in engagement with the edge of a rail base.

12. A device according to claim 11, in 120 which the body makes a driving fit on the rail base.

13. A device according to claim 11, in which the body holding means is a member hooked at one end to engage the opposite 125 edge of a rail base from the body and extending under the rail and between the body arms, the portion extending between the body arms being wedge-shaped.

14. In combination with a device accord- 130

ing to claim 13 a key holding the hook member in compression within the body.

15. A device according to claim 11, in which the holding member comprises a strip of resilient material hooked at one end to engage the opposite edge of a rail base from the body and extending transversely under the rail and between the body arms and bent upon itself to form an enlarged wedge-shaped portion in engagement with the body web.

16. In a rail anchor, a body notched to embrace the edge of a rail base and having a seat below the rail base inclined in the same direction as the adjacent upper surface of the rail base but to a greater degree, and a wedge-shaped holding member passing in compression through the body between the inclined seat and the base of a rail and adapted to engage the opposite edge of the rail base from said body and to urge the body toward the rail axis.

17. A device according to claim 16, in which the body holding member is resilient.

25. 18. A device according to claim 16, in which the holding member is maintained in compression by a key extending transversely of the rail.

30. 19. A device according to claim 16, in which the holding member is a strip of resilient material bent upon itself to form the wedge-shaped portion.

35. 20. A rail anchor comprising a pair of parts relatively slidable in a horizontal plane and adapted to clasp between them a rail base, the contact surfaces of said members being inclined and one of the members

being in compression between the other member and a rail, whereby the second member is urged along the first.

21. A device according to claim 20, in which the first member is resilient and exerts expansive pressure between the second member and the rail base.

22. In combination with a device according to claim 20, a key arranged transversely of the rail holding said first member in compression.

23. In a rail anchor, a body adapted to engage one edge of a rail base and having a seat below the rail base inclined in the same direction as the adjacent upper surface of the rail base adjacent the body, a holding member passing between the body seat and the rail base and adapted to engage the opposite edge of the rail base from said body, and a key adapted to be inserted between the rail base and said holding member.

24. In a rail anchor, a body adapted to engage one edge of a rail base and having a seat below the rail base inclined in the same direction as the adjacent upper surface of the rail base, a holding member passing between the body seat and the rail base and adapted to engage the opposite edge of the rail base from said body, said member being adapted to be in compression between the rail base and seat and to urge the body and holding member toward those edges of the rail base opposite the edges they engage.

70 In witness whereof, we have hereunto set our hands.

FRANCIS W. COOPER.
HENRY STEADWORTHY.
